UNITED STATES PATENT OFFICE.

WILLIAM B. ROSS, OF EL MODENO, CALIFORNIA.

WIRE STRETCHING AND TWISTING TOOL.

1,266,053.

Specification of Letters Patent. Patented May 14, 1918.

Application filed July 19, 1917. Serial No. 181,601.

To all whom it may concern:

Be it known that I, WILLIAM B. ROSS, a citizen of the United States, residing at El Modeno, in the county of Orange and State of California, have invented certain new and useful Improvements in Wire Stretching and Twisting Tools, of which the following is a specification.

This invention relates to combined pliers and wire twisters.

The object of the invention is to provide a pair of pliers equipped with means for twisting and securing wire loops around the ends of hose or other places where similar wire fastenings would be required and which does not in any way interfere with the use of the pliers in performing their usual functions.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a side elevation partly in section of a pair of pliers constructed in accordance with this invention and with the jaws shown open ready for tightening the wire loop which is engaged therewith, and

Fig. 2 is an edge view of the pliers in closed position and with the wire removed.

In the embodiment illustrated, the implement constituting this invention comprises a pair of pliers having the usual jaws 1 and 2 pivoted together upon a fulcrum bolt 3 after the manner of ordinary pliers and having lever handles 1' and 2'. The free ends of both jaws 1 and 2 are formed with flat faces 4 between which any object to be gripped may be held. The flat face 4 of jaw 2 has a groove 5 extending longitudinally from its outer end inward and communicating with a bore 6 which extends transversely through said jaw end and connects said groove 5 with another groove 7 arranged around the curved outer edge of jaw 2 and which is designed to receive the wire to be tightened and twisted. The wire for this purpose is here shown in the form of a loop L which may be wrapped around

the end of a hose, a bundle of metal rods or any object to be secured thereby and has one end thereof laid in the groove 7 and extended around the end of jaw 2, being placed in the groove 5 formed in the flat face 4 thereof and with its terminal extended through the transverse bore 6 as is shown clearly in Fig. 1 and by means of which said wire end is securely held. The other end of this wire extends rearwardly through groove 7 and has the terminal thereof threaded through an apertured lug 8 carried by the lever handle 1' of jaw 1 and which is preferably cast integral therewith as is shown clearly in Fig. 1. It will thus be seen that these ends of the wire will be securely held so that when the handle levers 1' and 2' are compressed toward each other, a pulling action will be exerted on the loop L thereby tightening the loop around the object to be secured and after the desired tightness has been obtained, the turning of the pliers will operate to twist the ends of the wire and thereby securely tie them. The terminals of the wire may then be disengaged from the pliers and said pliers used to cut off these ends close to the loop, wire cutters shown at 10 being provided for this purpose and which are usually carried by pliers of this character.

It will thus be seen that when the wire has been threaded through the pliers in the manner above described that the grooves 5 and 7 will operate to prevent it from slipping laterally and the tightening and twisting operation may be accomplished with the exertion of a minimum amount of force and in a very short time without in any way interfering with the usual functions of the pliers, as the groove 5 formed in the flat face 4 of jaw 2 extends throughout a portion only of the width of said face and therefore would not interfere with the clamping action of this jaw.

From the foregoing description, taken in connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that the device shown is merely illustrative and

that such changes may be made as are within the scope of the claimed invention.

I claim:—

1. A wire tightening and twisting implement comprising a pair of lever handles pivotally connected at one end and one having a forwardly extending jaw with a bore extending transversely therethrough from its inner face to its outer edge and adapted to receive one end of a wire to be tightened, an apertured lug carried by the other handle and opening longitudinally of said handle to receive the other end of the wire to be tightened whereby the movement of said handles toward each other will operate to stretch or tighten the wire, and wire retaining means to hold the two ends thereof in longitudinal alinement to provide for a direct pull being exerted on the wire.
2. An implement of the class described

comprising a pair of lever handles pivotally connected at one end, one of said handles having a jaw with a bore extending from its inner face through its rear edge with a wire receiving groove in its inner face leading from said bore to the outer end of said jaw, said jaw having another groove arranged around its outer edge and communicating with said first mentioned groove and extending rearwardly beyond said bore to form wire retaining means to prevent its lateral displacement, and an apertured lug carried by the other handle. 25 30

In testimony whereof I affix my signature in presence of two witnesses.

WILLIAM B. ROSS.
